GARTER.

Application filed October 19, 1927. Serial No. 227,271.

This invention relates to apparel and more particularly to a garter of the leg-encircling type.

One object of the invention is to provide a garter having the elastic usually provided in a leg-encircling band omitted, so that the garter may be laundered when it becomes soiled without losing its ability to remain in place about a leg.

10 Another object of the invention is to securely but releasably retain the band in a leg-encircling position through the medium of a resilient anchoring element carried by a pad forming a part of the garter and so located that when engaged with a fastener carried by one end of the band, the pad will be disposed beneath the anchor and fastener and prevent them from coming in contact with the leg.

20 Another object of the invention is to provide improved hose engaging means including a strip of fabric carried by the pad and folded to provide depending loops, one of which is to extend beneath a sock and carries a button and the other loop carrying a clip to be engaged with the button.

Another object of the invention is to so fold the fabric strip and so secure it upon the pad that it may not only carry the button and cooperating clip to engage a sock but also carry the anchor for engaging the fastener carried by the leg-encircling band.

The invention is illustrated in the accompanying drawing, wherein:

35 Figure 1 is a perspective view of the improved garter.

Figure 2 is a sectional view through the garter taken on the line 2-2 of Figure 1.

Figure 3 is a vertical sectional view 40 through the garter taken on the line 3-3 of Figure 1.

Figure 4 is a transverse sectional view through the button engaging clip, taken on the line 4-4 of Figure 1.

45 The garter constituting the subject matter of this invention is of the leg-encircling type and includes a pad 1 formed of inner and outer layers or plies 2 and 3 between which one end of the leg-encircling band

50 4 is secured, as shown in Figure 2. The band 4 extends transversely of the pad from one side thereof and carries a slide 5 to which the other end of the strip of fabric forming the band is secured after being

passed through the loop 6. The loop, 55 which constitutes a fastener for the free end of the band, is formed of wire and is twisted to provide an eye 7 which projects from its outer side. By adjusting the slide the length of the band may be controlled and 60 the band thereby caused to have a snug fit about the leg when in place. The pad and the band may be formed of any fabric having sufficient strength, such as duck or light weight canvas and since they are formed of fabric they may be washed without deteriorating.

In order to support a sock, there has been provided a sock engaging element which is indicated in general by the numeral 8. This 70 sock engaging element consists of a narrow strip of fabric 9 which is disposed vertically against the outer face of the pad 1 and sewed thereto by stitches along its sides. The strip 9 extends downwardly from the 75 pad and is folded upwardly and secured to the pad by stitches 10 to provide a depending loop 11 and is then again extended downwardly and upwardly and secured by stitches, as shown at 12, to provide a shorter 80 loop 13. In the preferred form, the stitches 10 extend through the portion of the strip forming the upper loop so that the two loops will be securely fastened together and to the pad and a very strong securing means 85 for the loop provided. Before the strip 9 is folded to form the loops a bead or button 14 and a latch or keeper 15 are threaded upon the strip and so disposed thereon that when the strip is folded and secured to provide the two loops, the button 14 will be carried by the lower loop and slidable longitudinally thereon toward and away from its lower end and the latch or keeper 15 will be suspended from the upper loop. A 90

slot or passage 16 which tapers downwardly, is formed in the sheet metal latch or keeper 15 and along the sides of the slot the keeper is formed with tongues 17 which are folded against its inner face, as shown in Figure 100 4, thereby providing smooth edges which will prevent a sock from being accidentally torn when engaged with the garter. The upper end portion of the strip 9 is folded, as shown in Figure 1, to provide a transversely extending portion which is folded under and secured to provide a side loop 18 and this side loop carries an anchor 19,

The anchor 19 is formed of resilient wire bent to assume a U-shape and has one arm 20 bent to provide an eye 21 engaged in the side loop 18 and its other arm bent to provide a hook or bill 22 to be engaged in the eye 7 of the fastener 6, and securely but releasably retain the leg-encircling band in encircling engagement with a leg.

When the garter is in use, the band 4, 10 after being adjusted by the slide 5 for proper length, is passed about the leg and its free end portion overlaps the pad so that the hook 22 of the anchor may be engaged in the eye 7. The lower loop 11 of the sock 15 engaging means is placed under the sock and the clasp 15 disposed over the sock so that the button 14, together with a portion of the sock and a portion of the loop, may be passed through the slot 16 in the latch and 20 wedged tightly in the lower portion of the slot. Since the edge portions of the metal from which the latch is formed are folded inwardly under the sides of the slot, there will be no danger of the sock being accidentally cut or worn through when it is 25 tightly wedged in the lower portion of the slot. In view of the fact that the anchor 19 is formed of resilient wire, and its arms are moved apart in order to engage the bill 22 30 in the eye 7, the anchor will exert a pulling action which will hold the band tightly about the leg and prevent it from slipping. Therefore, the garter will be retained in its 35 proper position and the sock will be well supported. When the garter becomes soiled it can be washed with soap and water in the usual manner and will not be damaged as the band does not contain strands of rubber which would be liable to deteriorate through 40 the action of water or perspiration.

Having thus described the invention, what I claim is:

1. A garter comprising a pad, a leg-encircling band carried by said pad, and hose engaging means carried by said pad and consisting of a strip of pliable material secured to the pad and extending downwardly therefrom and folded upwardly and secured to the pad to provide a depending loop and 50 again folded downwardly and upwardly and secured to the pad to provide a second de-

pending loop shorter than the first loop, a button carried by the first loop, and a keeper suspended from the second loop and having a slot formed therein to receive the button, 55 the first secured end portion of said strip extending upwardly against the pad above the second loop and folded to provide an extension extending transversely of the pad and secured thereto, and companion securing means carried by the side extension and said leg encircling band.

2. A garter comprising a pad, a leg-encircling band carried by said pad, and hose engaging means carried by said pad and 60 consisting of a strip of pliable material secured to the pad and extending downwardly therefrom and folded upwardly and secured to the strip to provide a depending loop and again folded downwardly and upwardly 65 and secured to the strip to provide a second depending loop shorter than the first loop, a button carried by the first loop, and a keeper suspended from the second loop and having a slot formed therein to receive the button, 70 the first mentioned end portion of said strip extending upwardly against the pad above the second loop and folded to provide a side loop extending transversely of the pad and secured thereto, a fastener carried by said leg encircling band, and a U-shaped keeper of resilient material having one arm formed with an eye engaged in the side loop and its other arm formed with a bill adapted to be 75 releasably engaged with said fastener.

3. A garter comprising a pad, a leg-encircling band extending from one side of said pad and having one end secured thereto, a fastener carried by the free end of said band, hose-engaging means carried by said pad and including a pliable strip depending from the pad and having its upper portion secured against the outer surface of the pad and its upper end folded to provide a side extension overlying the pad, the side extension being provided with means for engagement with the fastener carried by said band, and hose-gripping means carried by the depending portion of said strip.

In testimony whereof I affix my signature. 100

RUSH O. STRINGFELLOW. [L. s.]
